J. T. & M. L. Bever,

Ironing Table,

N° 37,804.

Patented Mar. 3, 1863.

Fig. 3.

UNITED STATES PATENT OFFICE.

JOHN T. BEVER AND MARIA L. BEVER, OF SPRINGFIELD, ILLINOIS.

IMPROVED IRONING-STAND.

Specification forming part of Letters Patent No. 37,804, dated March 3, 1863.

To all whom it may concern:

Be it known that we, JOHN T. BEVER and MARIA L. BEVER, of Springfield, in the county of Sangamon and State of Illinois, have invented a new and useful improvement in ironing-stands, including clothes-rack and compartments for clothing, and, when not in use for ironing purposes, has a receptacle for mattress or cushion; and we do hereby declare that the following is a full, clear, and exact description thereof, reference being had to the accompanying drawings, making a part of this specification, of which—

Figure 1 is a perspective view showing the adjustable leaf F attached, and in an elevated position for receiving the clothes upon. Fig. 2 is also a perspective view, showing the poles J J J and cords K K K in position. Fig. 3 is a sectional perspective view showing the side slide, H, removed from the frame D D; the leaf F in position for ironing upon, and a view of the interior compartments, B B.

This invention is constructed as follows:

a a are uprights or end pieces, having grooved dovetails to receive cross-frames B B, which are made permanent by wedges c c c. This constitutes the frame D D.

F is a half-oval leaf, resting upon uprights a a, attached by a hinge at the square end to upright a; and capable of being removed at will, said leaf F to be used for ironing clothes upon, greatly facilitating the labor thereof, being always conveniently put in place, and by elevating the leaf to a proper height the clothes—such as shirts, skirts, dresses, &c.—can be easily thrown over the smaller end adapted to that purpose, and when let down in place again the garment can be revolved around leaf F during the process of ironing, which gives the operator access to all the parts, and prevents the folds from pasting together. The garment is withdrawn by raising the leaf F upon its hinge in like manner.

Cords K K K are for the reception of the ironed garments.

g g g g are grooved brackets fastened to uprights a a to receive side slides, H H. Said side slides, when in place, form a spacious compartment for clothing between cross-frames

B B, and is of easy access by raising either side slide, which works freely in grooves g g.

i i are cleats fastened to the ends of frame D, on the outer parts of a a, containing mortises for the reception of poles J J J, said poles containing a number of small knobs or pins to receive and hold in place cords K K K, which are formed of one continued cord drawn tightly around each knob, thereby forming a series of cords or lines for clothes, one above another, at sufficient angle not to conflict with each other.

When the process of ironing and airing the clothes is sufficiently accomplished, the poles J J J and cords K K K may easily be removed from the frame D D, as also the leaf F, said leaf being detached by the removal of a pivot-wire from the hinge. The removal of poles, cords, and leaf being accomplished, the mattress or the cushion can be placed upon the upper cross-frame B, the side slides, H H, projecting some inches above the cross-frame B.

What we term an "ironing-stand" complete consists of a compartment for depositing newly-washed clothes, that they may be all kept in place and free from exposure to dust, until convenience suits for them to be ironed. The mattress L being removed for the time being, the space it occupied can be used for holding the dampened or sprinkled clothes preparatory to ironing, thereby avoiding the cumbersome use of baskets, &c.

Having thus described our improvement, what we claim as our invention, and desire to secure by Letters Patent, is—

The combination of leaf F with, frame D D and slides H H, poles J, and cords K, when arranged with the receptacle for clothing or mattress, substantially as and for the purposes set forth.

In testimony whereof we have hereunto signed our names before two subscribing witnesses.

JOHN T. BEVER.
MARIA L. BEVER.

Witnesses:

JOHN E. ROSETTE,
WILLIAM DEECOING.
